HARRISON TAYLOR CRONK, OF NEW YORK, N. Y., ASSIGNOR TO CRONK-SALTER COMPANY, OF NEW YORK, N. Y., A CORPORATION OF NEW YORK.

FLUID-CONDUIT IN CLOSET-BOWLS.

1,308,581.

Specification of Letters Patent.

Patented July 1, 1919.

Application filed February 9, 1915. Serial No. 6,988.

To all whom it may concern:

Be it known that I, HARRISON TAYLOR CRONK, a citizen of the United States, residing in the city, county, and State of New York, have invented certain new and useful Improvements in Fluid-Conduits in Closet-Bowls, of which the following is a specification.

One type of closet-bowl in general use is provided with a flushing rim extending about opposite sides thereof toward the front of the bowl, which rim is supplied with water through a single rear inlet from a supply pipe. Where the feed pressure is relatively low the water has sufficient time to divide more or less equally and each side of the rim is supplied with its quota of water. However, should the pressure adjacent the inlet to the rim be relatively high and especially where the water is admitted through one of the sides at the rear portion of the bowl, the tendency of the water is to continue in its general direction from the water inlet, pass the inlet at the near side of the rim and about the side of the rim opposite the inlet. This results in the feeding of a larger volume of water per unit of time down one of the sides than is fed down the side adjacent the water inlet.

One of the objects of the invention is to provide a conduit for directing the flushing water in substantially equal quantities per unit of time through the pair of openings in a forked passageway.

I attain this object broadly by positioning a tube in the main water passageway, said tube having a loose fit therein and provided with a closed end and with three openings in the side thereof, the two outside openings communicating with the two openings of the forked passageway.

Another object of my invention is to provide a simple form of attachment for controlling the rate and force of water fed to the bowl so that the same type of bowl may be used with the different pressure services now in general use.

Various other objects and advantages of the invention will be in part obvious from an inspection of the accompanying drawings and in part will be more fully set forth in the following particular descrip-

tion of one form of mechanism embodying my invention, and the invention also consists in certain new and novel features of construction and combination of parts hereinafter set forth and claimed.

Referring to the accompanying drawings:

Figure 1 is a plane view of the top of a closet-bowl with portions adjacent the water inlet broken away to show a preferred embodiment of my invention installed in position;

Fig. 2 is a side elevation of the rear portion of the bowl adjacent the water inlet;

Fig. 3 is a side elevation of the tube removed from the bowl; and

Figs. 4 and 5 are modified forms of the tube shown extending into the top and rear side of the bowl.

There is illustrated a conventional form of water-closet bowl 4, each side of the seating rim of which is provided with a flush water conduit 5 both of said conduits opening from a compartment 6 in the upper portion of the bowl adjacent the rear end thereof. Transversely opposite ends of the compartment are opened to the outside and a tube 7 inserted through one of the openings in which position it is fastened by providing one end with a closing cap 8 adapted to bear against the circular shoulder 9 outlining the opening. The opposite end of the tube is threaded and a rubber washer 10 inserted over the threaded end and tightened into engagement with a shoulder 11 by means of a nut 12 disposed between which nut and washer is a friction ring 13. The side of the tube is provided with a pair of spaced apart apertures 14 opening into the conduits 5. The portion of the tube between these apertures is provided with a relatively small aperture 15 and the adjacent wall outlining the compartment is slightly spaced from this small intermediate aperture.

Water admitted under pressure to the open end of the tube from a supply pipe 16 coupled to the threaded end of the tube passes through the tube, through the conduits or bores 5 and into the interior of the bowl through flush fluid outlets 17. If desired, the bore of the tube may be constricted in advance of each of the openings

to the passageway in the rim by providing apertured plugs 18 for insertion in place.

Instead of inserting the tube transversely into the bowl, the plumbing connections 5 may require that the supply of liquid be introduced preferably through the top or rear side of the bowl into the compartment 10. In this case the tube may be formed with an annular flange 19 designed to fit 15 against the inner wall of the compartment with a lock nut 20 threaded thereto and having a tight fit with the outer wall of the bowl about the inlet 21 to the compartment. The tube when inserted into place vertically 20 may have one or more side openings 22 for directing the water into one or both of the conduits 5 and when inserted horizontally through a rear inlet may have the inner end bifurcated to form passageways or nozzles 23 for directing the water to the conduits.

In operation, the flow of water through the supply pipe is directed to the tube and flows through the two outside apertures 25 leading to the conduits about opposite sides of the rim. Water will also pass through the intermediate aperture to form a ring of water surrounding the tube and tending to separate the compartment into two portions, 30 so that the water from the end apertures will not pass into the conduits on the opposite side of the bowl. Walls of water will also form in the compartment adjacent opposite ends of the tube so that the flushing 35 streams passing through the end openings into the conduits will pass through the compartment between more or less fixed walls of water.

Without a device of this character the 40 tendency of the water projected through the inlet to the bowl would be to travel about the opposite side of the rim and little or no water would pass directly into the side of the rim adjacent the inlet. With the tube 45 in place as described the flow of water even when under heavy pressure is divided with approximately an equal rate of flow to the two conduits.

It is possible to insert tubes of different 50 cross-sectional area of bore and with openings of different size and character to regulate the flow from the supply pipe to the bowl. In casting the bowls it is practically impossible to insure uniformity of bore in 55 the water conduits and accordingly there is a variation in the supply of water admitted thereto but the tubes herein described may be made of metal, preferably brass, may be made of any desired diameter and can be 60 made to fit the bores cast in the bowl irrespective of their variations from standard dimensions.

While I have shown and described, and 65 have pointed out in the annexed claims, certain novel features of my invention, it will

be understood that various omissions, substitutions and changes in the form and details of the device illustrated and in its operation may be made by those skilled in the art without departing from the spirit of the invention.

Having thus described my invention, I claim:

1. A closet-bowl having a compartment therein opening through one side of the bowl 75 and a pair of flushing conduits leading from said compartment, a tube insertible into said compartment and provided with a pair of spaced apart apertures leading to said flushing conduits and means for supplying fluid 80 to said tube.

2. A closet-bowl having a compartment therein opening through one side of the bowl and a pair of flushing conduits leading from said compartment, a tube insertible into 85 said compartment and provided with a pair of spaced apart apertures leading to said flushing conduits and means for supplying fluid to said tube, the portion of said tube between the apertures being spaced from the 90 adjacent wall of the compartment, said portion being provided with an aperture adapted to form a wall of water about the tube between the streams flowing from the first named pair of apertures.

3. A closet-bowl having a transversely disposed passageway in the rear thereof and having a bore leading from said passageway to a flush fluid outlet, a tube adapted to be positioned in said passageway and having 100 an opening in the side thereof adapted to open to said bore, means for supplying a flushing fluid to one end of said tube, said tube having a constriction in the bore thereof positioned between said means and said 105 opening.

4. A closet bowl having a transversely disposed passageway in the rear thereof and having a pair of conduits leading from said 110 passageway to flush fluid outlets, a tube adapted to be positioned in said passageway and having outlets therefrom spaced from but opening directly to said conduits and means for supplying a flushing fluid to said tube.

5. A closet bowl having a relatively wide 115 passageway therein and horizontally disposed conduits leading therefrom directly to the interior of the bowl, a tube extending lengthwise within the passageway and spaced from the conduits and means for supplying the flushing fluid for the bowl to said tube.

6. A closet bowl having a rim seat, flushing conduits extending about opposite sides 125 of said seat, said bowl having a passageway therein constituting an enlargement of said conduits at their meeting point, a water supply tube provided with three side openings adapted to be inserted into said passageway, 130

the two outside openings each designed to supply flush water directly to the conduit on its adjacent side and the center opening designed to supply water to the portion of the 5 passageway positioned between the two outside openings.

Signed at New York city, in the county of

New York, and State of New York, this 3rd day of February, A. D., 1915.

HARRISON TAYLOR CRONK.
